UNITED STATES PATENT OFFICE

ARTHUR R. SMITH, OF SCHENECTADY, NEW YORK, ASSIGNOR TO GENERAL ELECTRIC COMPANY, A CORPORATION OF NEW YORK

SUPERHEATER

Application filed November 24, 1926. Serial No. 150,804.

The present invention relates to superheaters such as are used in connection with boilers, for example, for superheating the vapor generated in the boiler. The invention is well adapted for use in the superheating of steam in steam boilers and this application of the invention is specifically illustrated in the drawing and described in the specification. It is to be understood, however, that the invention is not limited necessarily to this application.

In the production and utilization of highly superheated steam, that is steam heated to temperatures in excess of 750° F., one of the problems is that of providing containers and conduits for steam having temperatures of this order. This is because at such high temperatures the material of the container or conduit becomes weakened so that it is rendered incapable of withstanding the pressure of the steam without becoming overstressed. In this connection, it is more difficult to produce such hot steam economically than it is to utilize it for the reason that in the utilization of such steam the temperature of the container or conduit, the strength of which is a limiting factor, will always be at a temperature somewhat less than the steam, whereas in the production of superheated steam the temperature of the container or conduit in which the steam is superheated must always be at a temperature higher than that of the steam.

The object of my invention is to provide an improved container or conduit especially adapted for use as a superheater tube in the production of superheated steam, and for a consideration of what I believe to be novel and my invention, attention is directed to the accompanying description and the claims appended thereto.

In the drawing, Fig. 1 is a top plan view of superheater tubes embodying my invention; Fig. 2 is an enlarged view of a portion of one of the tubes shown in Fig. 1; Fig. 3 is a view similar to Fig. 2 of a modification, and Fig. 4 illustrates the arrangement of the tubes in a boiler.

Referring to the drawing, 5 indicates the furnace walls of a boiler setting, 6 indicates the boiler tubes, 7 indicates the steam drum

and 8 indicates superheater tubes which are connected to the steam drum and which embody my invention.

Each superheater tube comprises a central pipe or container 9 surrounding which are spirally-wound pipes 10, pipes 10 being held in spaced relation to pipe or container 9 by suitable spacing means 11. In Figs. 1 and 2 the spacing means is shown as being in the form of a ribbon formed from suitable material, such as steel, spirally wound edgewise on container or pipe 9. Pipe 10 is wound directly on ribbon 11 and acts through ribbon 11 to reinforce pipe or container 9. Ribbon 11 comprises three strips wound spirally triple pitch and pipe 10 comprises two lengths of pipe wound spirally double pitch. The ribbon and pipe are wound one right hand and the other left hand. Pipe 10, ribbon 11 and container or pipe 9 may be fastened together in any suitable manner such as by means of brazing or welding. The lengths of pipe 10 are connected at one end to a steam supply header 12 which in turn is connected to the steam space in drum 7 by a conduit 13. The other ends of the lengths of pipe 10 are connected to the outer end of central pipe 9. The inner end of central pipe 9 is connected to a discharge header 14 from which superheated steam is conveyed by a conduit 15.

With the above described arrangement, pipe 10 serves as a reinforcing means for the walls of pipe 9.

In use, the steam flows from header 12 through the lengths of pipe 10 to the outer end of inner pipe 9 and then through pipe 9 to header 14. The tube as a whole is located in the path of the furnace gases so that the steam in passing through the pipes of the tube becomes superheated. The steam flows first through the outer pipe 10 and then through the inner pipe 9 so that the initial superheating takes place in outer pipe 10 and the final superheating takes place in inner pipe 9. This means that outer pipe 10 has a temperature lower than inner pipe 9. By suitably arranging and proportioning pipes 10 and 9 relatively to each other, the desired amount of superheating may be effected in each, the arrangement being such that pipe

10 will not be heated to a temperature such that it is weakened due to its temperature. On the other hand, pipe 9 may be heated to a temperature such that the tensile strength of the material from which it is formed will be depreciated but this will be offset by the reinforcement which it obtains from the spirally-wound pipe 10.

Spirally wound ribbon 11 in addition to performing the function of struts or supports between central pipe 9 and outer pipe 10 performs also the function of providing a means for increasing the heat-absorbing surface for central pipe 9. It will be seen that ribbon 11 is in engagement with pipe 9 over considerable area while it is in engagement with pipe 10 only at spaced points. As a result, the major portion of the heat absorbed by ribbon 11 will be conveyed to the steam in pipe 9. By varying the length and size of pipes 10 and 9 and the amount and arrangement of ribbon 11, the desired distribution of heat between pipes 10 and 9 may be obtained. As an example of this, assume for example, that it is desired to superheat steam from 475° to 1000° F. Under these circumstances the arrangement may be such that the steam while passing through pipe 10 will be superheated from the initial temperature of 475° F. to a final temperature of the order of 700° F., and while passing through pipe 9 it will be superheated from an initial temperature of the order of 700° F. to the final temperature of 1000° F.

In Fig. 3 is illustrated a modification wherein the struts or supports for outer pipe 16 are in the form of cast rings 17 which surround central pipe 18 and are suitably attached to it and to pipe 16.

In both the arrangements illustrated it will be seen that a central pipe carrying highly superheated steam is reinforced by a surrounding pipe carrying superheated steam of lower temperature through the intermediary of supports or struts which form also means for conveying heat to the steam in the central pipe.

While the invention is especially well adapted for use as a superheater and has been so illustrated and described, it is to be understood that it is not limited thereto necessarily but that it may be utilized wherever found applicable. For example, it may be utilized in any instance wherein it is desired to reinforce a conduit or container which is subjected to fluid of high temperatures.

In accordance with the provisions of the patent statutes, I have described the principle of operation of my invention, together with the apparatus which I now consider to represent the best embodiment thereof, but I desire to have it understood that the apparatus shown is only illustrative and

that the invention may be carried out by other means.

What I claim as new and desire to secure by Letters Patent of the United States, is:

1. A superheater tube comprising an inner conduit, supporting struts on said inner conduit, and an outer conduit spirally wound on said struts and forming a reinforcing means for the inner conduit. 70

2. The combination with a conduit 75 through which highly heated fluid flows, of means for reinforcing it comprising a spirally wound conduit through which fluid of lower temperature flows, and a plurality of spaced circumferentially extending, radially projecting members located between said conduits in engagement with the first named conduit and upon which said second named conduit is tightly wound. 80

3. The combination with a conduit 85 through which highly heated fluid flows, of means for reinforcing it comprising spaced circumferentially extending members arranged edgewise on the conduit, and a conduit spirally wound on said members 90 through which fluid of lower temperature flows.

4. The combination with a conduit 95 through which highly heated fluid flows, of means for reinforcing it comprising ribbon spirally wound edgewise on such conduit, and a tube spirally wound on said ribbon and through which fluid of lower temperature flows.

5. A superheater tube for a boiler or the like, said tube comprising outer and inner pipes through which the fluid to be superheated flows in series, said inner pipe being provided over a major portion of its length with a plurality of axially spaced radially-projecting supports, and said outer pipe being wound thereon to form a reinforcing means for the inner pipe. 100

In witness whereof, I have hereunto set my hand this 23d day of November, 1926.
